UNITED STATES PATENT OFFICE

HAROLD C. EDWARDS, OF KANSAS CITY, MISSOURI

DESIGN FOR A RADIOCABINET OR SIMILAR ARTICLE

Application filed September 11, 1930. Serial No. 36,942. Term of patent 3½ years.

To all whom it may concern:

Be it known that I, HAROLD C. EDWARDS, a citizen of the United States, residing at Kansas City, in the county of Jackson and State of Missouri, have invented a new, original, and ornamental Design for a Radiocabinet or Similar Article, of which the following is a specification, reference being had to the accompanying drawing, forming part thereof.

The figure is a perspective view of a radiocabinet or similar article showing my new design.

The rear face of the cabinet is unornamented.

I claim:—

The ornamental design for a radiocabinet or similar article, as shown and described.

HAROLD C. EDWARDS.
